MUSICAL PLAY PEN TOY

Sam Zuckerman, Arverne, N. Y., assignor to
Ever-Rite Toy Co., Inc., New York, N. Y., a
corporation of New York

Application August 10, 1946, Serial No. 689,677

1 Claim. (Cl. 84—403)

1

My present invention relates to a musical toy and more particularly to a toy of the type including a number of bars or chimes to be struck, which bars or chimes are so arranged in a support that they may readily be suspended across the bars or rails of a play pen, crib or similar article of furniture; and also the structure is so arranged that it may be stood on the floor and operated in the same manner as an xylophone.

Also my invention relates to novel means for suspending musical chimes or bars in respect to support which carries the same.

Specifically, my invention contemplates an arrangement of chimes or bars on a pair of opposite strings, the chimes or bars being spaced by appropriate spacers and the strings being carried by appropriate supporting bars. The supporting bars are provided with means, such as a string, for securing the supporting bars and hence the whole instrument across the rails or bars of a play pen, crib or similar article; and the supporting bars are also provided with openings for receiving and holding leg-like members so that the entire instrument may be rested on the floor to be played.

Thus, the primary object of my invention is the provision of a novel musical toy consisting of a plurality of musical chimes or bars so arranged that the toy may be attached across the rails or bars of a play pen, crib or similar article of furniture, and also so arranged that the entire toy may be stood on the floor to be played.

Thus, the primary object of my invention is the provision of a novel musical toy consisting of a plurality of musical chimes or bars so arranged that the toy may be attached across the rails or bars of a play pen, crib or similar article of furniture, and also so arranged that the entire toy may be stood on the floor to be played.

Another object of my invention is the provision of novel suspension means for chimes or musical bars comprising a pair of spaced taut strings on which the chimes and musical bars are arranged in spaced relation.

Another object of my invention is the provision of novel support means for a musical toy of the xylophone type.

The foregoing and many other objects of my invention will become apparent in the following description and drawings in which

Figure 1 is a plan view showing one form which my novel musical toy may take.

Figure 2 is a side view of the toy of Figure 1 showing supporting leg members secured therein.

2

Figure 3 is a side view of one of the chimes or bars of the musical toy of Figure 1.

Figure 4 is a side view of a modified form of the chime member of the musical toy of Figure 1.

Figure 5 is a side view of a play pen or crib rail showing the manner in which musical chimes or bars may be suspended therein in accordance with my invention.

Figure 6 is a cross-sectional view showing a modified form of musical chime or bar for use in connection with the structure of Figure 1.

Figure 7 is a side view of a modified form of spacing member.

Referring now to Figures 1 and 2, I have here shown my musical toy which comprises a pair of support bars 10 and 11 provided with suitable openings 13, 14, 15, 16 into which the cross-bars 17, 18 are fitted to form a chime supporting structure. Cross-bar 17 is fitted into openings 15 and 13 of support bars 10 and 11, and cross-bar 18 is fitted into openings 16 and 14 of cross-bars 10 and 11.

The cross-bars are secured in the openings above mentioned in any suitable manner; preferably they are a tight force fit in the openings and securement therein may be assisted by suitable adhesive. The cross-bars 17 and 18 are provided with openings 20, 20a and 21, 21b between which the strings 22 and 23 are tensioned; that is, string 22 is tensioned between through-openings 20 and 20a of cross-bars 17 and 18, and string 23 is tensioned between through-openings 21 and 21b of cross-bars 17 and 18.

As will be seen from examination of Figure 1, the openings 20, 20a and 21, 21b are counter-bored to provide a suitable recess for knots or other holding means on the ends of the strings 22, 23. In the embodiment shown, however, the strings 22, 23 are extended, as hereinafter described, to form the securing means for the entire support.

The musical bars or chimes 30 (Figures 1 and 3) are hollow tubular members suitably dimensioned to provide an appropriate scale and are provided with the through-openings 31, 32 through which the strings 22 and 23 respectively pass. The series of chimes or bars 30 are spaced from the cross-bars 17, 18 by appropriate spacer members such as the balls 33, 33 which are also provided with through-openings for the strings 22 and 23 and the chimes or bars 30 are also spaced from each other by appropriate spacer members 35 in the form of spheres with through-openings for the strings 22, 23.

As seen in Figure 7, oval spacer members 37

may be used, thus decreasing the area of contact between the spacer member and the chimes, and of course a spacer member of any appropriate shape may be used. Thus the spacer members may be in the form of cubes so perforated that diagonally opposite corners of the cubes will engage and space the chimes or bars.

Also, as seen in Figure 4, the chimes or bars 30 are not necessarily limited to longitudinal members but may comprise ball or sphere-like members 40 with through-openings 41 to receive a string. In the case of the use of sphere-like chimes 40 of Figure 4, only one of the strings 22 would be necessary for any row of chimes and the utilization of two strings 22 and 23 would simply make it possible to use two rows of chimes in the same instrument.

While for simplicity of manufacture the hollow tubular chime 30 of Figure 3 is preferred, I may as shown in Figure 6 utilize a closed chime 45 having a closed end 46 with an opening 47 in the end, the opposite end being closed by the cap 48 secured in any suitable manner, the cap 48 also having an opening 51. Openings 50, 50 are provided so that the supporting strings may pass through the chime of Figure 6.

As shown in Figure 1, the strings 22 and 23 are extended beyond the outer sides of the cross-bars 17 and 18 through openings 20 and 21 to form the strands 122 and 123, which may be knotted, twisted or simply crossed at 100, 100. It is preferred that the string extensions 122, 123 be simply twisted around each other in a simple twist, as shown in Figure 1.

The strings 122, 123 are then extended at 223 and 222 where they pass through openings 60, 60 in the ends of support bars 10 and 11. Here the strings are knotted as shown at 61, 61, the knot being pulled extremely tight so that the strings 22 and 23 supporting the chime members will be taut. The strings are then extended at 323 and 322 where they pass through an appropriate opening in the ornamental balls 63, 63 and are extended therethrough to the securing strings 423 and 422. Strings 423 and 422 at each end may be tied across the rails or bars of a play pen, crib or similar article of furniture, or a pair of strings on each side may be looped to be worn around the neck of a child; or the strings on both sides may be extended and tied together to form a larger loop to enable the instrument to be worn around the neck of a child; or the strings may be utilized to hang the instrument in any suitable manner from any appropriate object so that the instrument may be played by an appropriate mallet.

Should it be desired to play the instrument as a xylophone on a horizontal support, then leg members 70, 70 may be force fitted into openings 71, 71 of the support members 10 and 11 so that the instrument may be placed on a horizontal surface and be played as a xylophone. These leg members 70 may readily be inserted and removed by the child so that the instrument may readily be changed from a floor or table-top in-

strument to a hanging or suspended instrument, as above described.

My novel support for musical chimes may of course be utilized in many varied and different ways. Thus, for instance, in Figure 5 I have shown my musical chime members 30 supported on strings 22 and 23 stretched between post members 117 and 118 of the crib or play pen railing 200. Thus, the musical instrument is in this manner built right into the crib, play pen or other similar article of furniture.

It will thus be seen that suspension means for the musical chimes 30 are free of any solid or rigid bar. Chimes 30 are supported and hung solely from the string members 22 and 23 which may vibrate readily and which permits the chimes 30 to vibrate without striking any solid support or other object.

The musical toy is arranged for a variety of purposes and is thus a composite toy which may be attached to an article of furniture, carried by a child or hung around a child's neck to be played by him, or which may be placed on the floor or table-top to be played.

In the foregoing I have described my invention solely in connection with a specific illustrative embodiment thereof. Since many variations and modifications of my invention will now be obvious to those skilled in the art, I prefer to be bound not by the specific disclosures herein contained, but only by the appended claim.

I claim:

A musical xylophone toy comprising a frame, a pair of strings supported by said frame, a plurality of spaced chimes supported by said strings and spaced thereby from said frame; pairs of aligned transverse openings in said chimes; said strings passing through the transverse openings in said chimes; each string passing through aligned openings, spacers supported on said strings between said chimes; transverse openings through said spacers; said strings passing through the openings of said spacers, support feet removably mounted in said frame; additional transverse openings in said frame, said strings being slidably mounted in said last-mentioned openings; the ends of the strings on each side being looped together; and additional means securing said ends of said strings together.

50
